COMBINED INCINERATOR AND WATER HEATER

Filed Dec. 10, 1928

UNITED STATES PATENT OFFICE

WILLIAM C. EPSTEIN, OF DAYTON, OHIO, ASSIGNOR TO THE DUO-TOR MANUFACTURING COMPANY, OF DAYTON, OHIO, A CORPORATION OF OHIO

COMBINED INCINERATOR AND WATER HEATER

Application filed December 10, 1928. Serial No. 324,937.

This invention relates to a combined incinerator and water heater and means for automatically controlling the same.

One object of the invention is to provide a combined incinerator and water heater having means for automatically controlling the operation of the burner by the flow of water through the heater.

A further object of the invention is to provide such a combined incinerator and water heater in which the burner will operate whenever water is withdrawn from the heater and which will be provided with means for continuing the operation of the burner after the flow of water has been discontinued.

A further object of the invention is to provide such a combined incinerator and water heater in which the burner will be caused to operate when water is withdrawn from the heater and having means for automatically interrupting the supply of fuel to the burner, independently of the flow of water, when the water in the heater reaches an excessive temperature.

Other objects of the invention will appear as the apparatus is described in detail.

The accompanying drawing is a vertical sectional view of a combined incinerator and water heater, with the controlling mechanism in elevation.

In this drawing I have illustrated one embodiment of my invention and have shown the same as applied to a water heater of the storage type but it will be understood that this particular embodiment has been chosen for the purposes of illustration only and that the apparatus may take various forms and may be applied to water heaters of various kinds.

In that form of the apparatus here shown the water heater comprises a tank 1 which may, if desired, comprise a part of a domestic water heating system. The tank is provided with a central vertical opening 2 extending entirely through the same, so that in cross section it is an annular form. The tank is preferably provided with an insulated outer wall, as shown at 3. The tank may be supported in any suitable manner and, as here shown, it is mounted on a base

casting 4 which may be provided with suitable standards or legs, not here shown. Mounted within the central opening 2 of the tank and spaced from the wall of that opening is a receptacle or hopper 5 adapted to receive and support the refuse or other material to be consumed. This hopper is preferably supported on the tank and is here shown as carried by a top casting 6 mounted on the tank. In the present instance the hopper is directly secured to a flanged ring 7 which overhangs the top casting 6 and is provided with a movable closure 8 to permit the insertion of the refuse. The lower portion of the hopper is slotted, as shown at 9, and the bottom wall of the hopper, which is not shown, is preferably in the form of a grate. The upper portion of the hopper is slotted, as shown at 10, to permit the fumes and products of combustion to escape into an annular passageway 11 which may be connected with a flue.

Mounted beneath the hopper, and preferably arranged within the base casting 5, is a burner 12 which is here shown as annular in form and as having inner and outer fuel openings 13 and 14. The burner is of such a size and so arranged that the flame from the inner fuel opening 13 will direct its heat against the bottom of the hopper and into the space between the hopper and the inner wall of the tank. The flame from the outer fuel opening will direct its heat against the bottom of the tank and upwardly through flues 15 arranged vertically in the tank. The burner is provided with a pilot burner 16 connected by a pipe 17 with a source of fuel supply, independent of the controlling means hereinafter described, so that the pilot burner may operate continuously.

Fuel is supplied to the main burner 12 through a supply pipe 18 and the flow of fuel through this fuel supply pipe is controlled by the flow of water through the tank, the latter being provided with the usual cold water inlet pipe 19 and the hot water outlet pipe 20, the outlet pipe leading to the hot water distribution system or other point of discharge. The controlling means for the fuel supply pipe may take various forms but

is here shown as comprising a valve 21 interposed in the fuel pipe 18 and connected with an actuating device 22 interposed in the cold water supply pipe 19 and of such a character that when all outlets are closed and no water is flowing through the heater the valve 21 will be closed, but when an outlet is opened and the pressure relieved the valve 21 will be opened to permit the flow of fuel to the burner. Controlling devices of this kind are well known and are commonly used in connection with instantaneous water heaters and therefore I have not shown in detail the construction of the controlling device. It will be apparent that whenever water is withdrawn from the heater fuel will be admitted to the main burner and will be ignited from the pilot burner and the main burner will continue to operate so long as water flows through the heater, and that the supply of fuel to the burner will be interrupted when the outlet is closed and water ceases to flow through the heater. The flame and products of combustion from the main burner will serve to simultaneously consume the material within the hopper and to heat the water in the tank and the heat generated by the burning of the refuse or other material in the hopper will also serve to heat the water in the tank. The hot water in the tank will maintain a relatively high temperature in the space surrounding the hopper, which constitutes a combustion chamber, and the material or refuse deposited in the hopper will be subjected to the drying action of heat before there has been any operation of the burner and between subsequent operations of the burner, thereby evaporating moisture therefrom and facilitating the burning thereof. It is desirable that the water in the tank should be maintained at a relatively high temperature both for the purpose of maintaining the hot water supply and for maintaining the drying action within the combustion chamber. The construction of the tank is such that the water therein will be very quickly heated during the operation of the burner but when large quantities of water are withdrawn the temperature will fall below that desired and in order to raise the temperature of the water to the desired degree the burner must continue to operate after the flow of water to the heater has been interrupted. For this purpose I have provided the heater with a second fuel supply pipe 23 which is connected with the fuel supply pipe 18 in advance of the valve 21, so that the flow of fuel through the second pipe, 23, is wholly independent of the valve 21. The flow of fuel through the second pipe, 23, is controlled by a thermostatic valve 24, the thermostat 25 of which extends into the water tank. This thermostat is so adjusted that it will open the valve in the supply pipe 23 when the temperature of the water falls below a predetermined

degree, say 115 degrees, and will close that valve when the temperature rises to a predetermined degree, say 140 degrees. Consequently if the amount of water withdrawn from the tank has been such as to lower the temperature of the water therein below the predetermined degree the valve 24 will be opened and when the flow of water is interrupted and the valve 21 is closed fuel will continue to flow to the burner through the pipe 23 until the temperature of the water has been raised to the desired degree when the valve 24 will be closed.

Should a hot water outlet be left slightly open there would be a continued small flow of water through the heater which might be sufficient to cause the valve 21 to remain open but would be so small that the operation of the burner would cause the water in the tank to be heated more rapidly than cold water could enter the tank through the supply pipe 19. Such a situation would cause the operation of the burner to continue after the refuse in the hopper had been consumed and the water heated to the desired degree and would result in a waste of fuel. Further, in extreme cases, the water might be heated to the danger point. I have therefore provided means other than the water valve 21 to control the flow of fuel through the main supply pipe 18. As here shown, a thermostatic valve 26 is interposed in the supply pipe 18 between the water valve 21 and the burner and has its thermostat 27 inserted in the water tank. This thermostat is so adjusted that the valve 26 will be closed when the water in the heater reaches an excessive temperature, say 160 degrees, but will be open at all other times. Consequently in the normal operation of the apparatus the valve 26 does not function but in the event the water in the heater is heated to an excessive temperature the valve 26 will be closed and the supply of fuel through the main supply pipe 18 cut off. Inasmuch as the thermostatic valve 24 will be closed before the valve 26 closes both fuel lines will be closed and will remain closed until the temperature of the water is lowered.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In an incinerating apparatus, a hopper to receive material to be consumed, a water heating element having an inlet and an outlet, a burner arranged beneath said hopper, a fuel supply pipe leading to said burner, means controlled by the flow of water through said heating element to control the operation of said burner, and means to maintain said burner in operation after the flow of water

through said heating element has been interrupted.

2. In an incinerating apparatus, a hopper to receive material to be consumed, a water heating element having an inlet and an outlet, a burner arranged beneath said hopper, a fuel supply pipe leading to said burner, means controlled by the flow of water through said heating element to control the operation of said burner, and means controlled by the temperature of the water in said heating element to maintain said burner in operation after the flow of water through said heating element has been interrupted.

3. In an incinerating apparatus, a structure comprising a combustion chamber, means to support material to be consumed within said combustion chamber, a water heating element arranged adjacent to said combustion chamber and having an inlet and an outlet, a burner arranged beneath said material supporting means, means controlled by the flow of water through said heating element for supplying fuel to said burner to consume the material within said combustion chamber and to heat the water in said water heating element, and other means controlled independently of the flow of water through said heating element to maintain the water in said heating element at such a temperature that the heat therefrom will tend to dry the material in said combustion chamber when said burner is not in operation.

4. In an incinerating apparatus, a refuse supporting element to receive material to be consumed, a water heating element arranged in such relation to said refuse supporting element that heat may be transmitted from one element to the other element, said water heating element comprising an inlet pipe and an outlet pipe, a main burner arranged beneath said elements, a pilot burner associated with said main burner, a fuel supply pipe leading to said main burner, a valve in said fuel supply pipe, means interposed in one of the pipes of said water heating element and controlled by the flow of water through the same to control the operation of said fuel valve, and means controlled by the temperature of the water in said water heating element to supply fuel to said main burner independently of said fuel valve.

5. In an incinerating apparatus, a refuse supporting element to receive the material to be consumed, a water heating element arranged in such relation to said refuse supporting element that heat may be transmitted from one element to the other element, said water heating element comprising an inlet pipe and an outlet pipe, a main burner arranged beneath said elements, a pilot burner associated with said main burner, two fuel supply pipes connected with said main burner, means controlled by the flow of water through said water heating element to con-

trol the flow of fuel through one of said supply pipes, a thermostatic valve interposed in the other supply pipe, and a thermostat connected with said thermostatic valve and extending into said water heating element.

6. In an incinerating apparatus, a refuse supporting element to receive the material to be consumed, a water heating element arranged in such relation to said refuse supporting element that heat may be transmitted from one element to the other element, said water heating element comprising an inlet pipe and an outlet pipe, a main burner arranged beneath said elements, a pilot burner associated with said main burner, two fuel supply pipes connected with said main burner, means controlled by the flow of water through said water heating element to control the flow of fuel through one of said supply pipes, a thermostatic valve interposed in the other supply pipe, a thermostat connected with said thermostatic valve and extending into said water heating element, a thermostatic valve interposed in the first mentioned supply pipe between the first mentioned controlling means and said burner, and a thermostat connected with the last mentioned valve and extending into said water heating element.

7. In an apparatus of the character described, a water heating element having an inlet and an outlet, a burner, means controlled by the flow of water through said heating element to supply fuel to said burner, and means controlled by the temperature of the water in said heating element to supply fuel to said burner independently of the first mentioned means.

In testimony whereof, I affix my signature hereto.

WILLIAM C. EPSTEIN.
